(57) CLAIM

The ornamental design for a textured orb oil lamp, as shown and described.

DESCRIPTION

FIG. 1 is a perspective view from the top of the textured orb oil lamp showing my new design;
FIG. 2 is a perspective view from the bottom thereof;
FIG. 3 is a top view thereof;
FIG. 4 is a bottom view thereof;
FIG. 5 is a side view of a first quadrant thereof;
FIG. 6 is a side view of a second quadrant thereof;
FIG. 7 is a side view of a third quadrant thereof; and,
FIG. 8 is a side view of a fourth quadrant thereof.
The broken line environmental showing is for illustrative purposes only and forms no part of the claimed design.
